UNITED STATES PATENT OFFICE.

CHARLES H. REUTER, OF HOXIE, KANSAS.

APPARATUS FOR RAISING OR LOWERING PUMP-PIPES.

1,110,961.

Specification of Letters Patent. Patented Sept. 15, 1914.

Application filed June 8, 1912. Serial No. 702,597.

To all whom it may concern:

Be it known that I, CHARLES H. REUTER, a citizen of the United States, residing at Hoxie, in the county of Sheridan and State 5 of Kansas, have invented new and useful Improvements in Apparatus for Raising or Lowering Pump-Pipes, of which the following is a specification.

This invention relates to apparatus for 10 raising and lowering pump pipes and sucker rods, the object of the invention being to provide a construction of apparatus of this character which will effectively lift a pipe or rod with a minimum amount of power, 15 and which will include means for positively holding or locking the pipe or rod against accidental falling during the lowering operation.

Another object of the invention is to 20 provide such locking means for preventing the accidental sudden fall of the pipe within the well which will embody an automatically locking dog and a releasing element therefor the latter being designed to be normally 25 maintained in inoperative position by the pipe and to be released on the fall of the pipe to a predetermined position to cause the dog to immediately respond and effectively grip the pipe and thereby prevent the 30 further movement of the same in one direction.

Figure 1 is a side view of the apparatus showing the same in use when lowering a 35 pipe, parts being shown in section. Fig. 2 is a similar view showing the clamp adjusted for raising the pipe, parts being shown in section. Fig. 3 is a side view of the opposite side of the apparatus. Fig. 4 is a horizontal section taken on line 4—4 of Fig. 40 1. Fig. 5 is a perspective view of the dog.

In describing the apparatus, it is said that a suitable frame such as that illustrated at 45 1 is employed, the same being so constructed that it can be readily mounted upon the platform of the well drilling machine, not shown. At the lower end, the frame is provided with a horizontal bar 2 on which is mounted the fixed jaw 3 and the adjustable jaw 4, the latter being designed to coöperate 50 with the jaw 3 so as to define therewith an

intervening guide through which the pipe or sucker rod is adapted to slide. The jaw 4 is provided with a bracket portion 5 in which the horizontal slot 6 is formed for the reception of the bolt 7 on the bar 2 of the frame 1. This construction is such that the jaws 3 and 4 are relatively movable so as to accommodate the passage of pipes or rods of different sizes therethrough. A nut 8 on the bolt 7 may be adjusted to bear against the bracket portion 5 of the jaw 4 whereby the latter can be effectively held in its adjusted position. At the upper end the frame 1 is provided with a horizontal bracket plate 9 in which the pipe or rod guide slot 10 is formed. A keeper 11 is pivoted at 12 to the plate 9, and as shown, said keeper is provided with an embracing portion 13 to partly engage around the rod or pipe to hold the same securely positioned in the guide slot. 17 The keeper carries a lever 14 which may be engaged behind the latch 15 on the plate 9 whereby the keeper is held in its adjusted position. An operating lever 16 is pivoted at 17 to the frame 1 and pivotally connected to said lever are the companion links 18 and 19, the latter being considerably longer than the former for a purpose to be hereinafter described. A clutch element or clamp 20 is pivoted at 21 to the links 19 the same having 27 formed therein a slot 22 whose end wall is beveled downwardly and outwardly to form a relatively sharp upper gripping edge 23. By forming the slot 22 as shown, the clamp 20 is provided with spaced fingers 24 which 37 are partly embraced by the hook like ends 25 of the removable keeper or retainer plate 26. Cotter pins or suitable fastening devices 27 are removably fitted to the fingers 24 and are designed to hold the plate 26 against 47 accidental displacement. The plate 26 is provided with an arcuate wall 28 which is disposed directly opposite the sharp edge 23 of the clamp so as to define therewith an intervening passage for movement 57 therethrough of the pipe or rod. A similar clamp 29 is pivoted at 30 to the links 18, the former being disposed above the clamp 20 and having formed therein a slot 31 whose end wall is beveled downwardly and 67

outwardly in an opposite direction to the end wall of the slot 22 so as to form an upper sharp arcuate gripping edge 32. This clamp is also provided with a removable keeper plate 33 which is similar to the plate 26 hereinbefore described. The clamp 29 carries a relatively short hook 34 to which is removably connected the lower end of the coiled spring 30', the upper end 10 of said spring being fixedly secured to the eye member 35 on the operating lever 16 and at a point thereon inwardly of the link 18. The clamp 20 carries a relatively long hook 36 which is removably fitted to the lower end 15 of the coiled spring 37, the latter being also secured at its upper end to the lever 16, inwardly of the link 19, as shown.

The operation is as follows for raising a pipe or rod: A pipe or rod is operatively fitted in the upper and lower guides of the frame and in the slots in the clamps 20 and 29 and the latter disconnected from the springs 30 and 37. Now, by rocking the lever 16 up and down the clamps 20 and 29 will be alternately moved toward and away from each other, the sharp edges 23 and 32 of the clamps being brought alternately into gripping engagement with the pipe to thereby cause the latter to move upward. When lowering the pipe, the springs 30 and 37 are connected with the clamps and under the tension of the springs, the clamps will be alternately made to grip the pipe only on their downward movement, there being sufficient play between the clamps to permit the step by step like fall of the pipe as the lever 16 is rocked. When lowering the pipe it is essential that means be employed for preventing the pipe from slipping and for causing the positive gripping of the lower clamp 20 against the pipe prior to the release of the clamp 29 therefrom, and in view thereof I provide a substantially bell-crank lever 38 which is pivoted at 39 to the frame 1. This lever has the free end of the arm 40 disposed above the plate 26. The arm 41 of this lever is provided with a lug 42 through which the adjusting screw 43 extends. A retractile spring 44 connects the arm 40 of the lever with the bar 2 of the frame 1 so that the free end of the arm 40 will be engaged against the keeper plate 26 on a predetermined movement of the lever 16 in a downward direction. One end of the screw 43 bears against one of the side members of the frame 1 and the screw is thereby capable of operation to vary the tension on the spring 44 as the occasion may demand. A slotted member 44' operatively connects 55 the upper and lower clamps together, being fitted to the pins 45 thereon whereby a predetermined movement of the lever 16 in an upward direction causes the upper clamp to engage against the pipe slightly prior to the

release of the lower clamp from said pipe. 65 As means to prevent the sudden fall of the pipe into the well in the event of the failure of the clamps 20 and 29 to respond properly, I provide a pivoted locking dog 46 upon the bar 2 of the frame 1. This dog is disposed above the fixed jaw 3 and it is provided with a gripping surface 47 which is designed to partly embrace the pipe. This dog is yieldingly held upwardly at an angle to the bar 2 through the medium of the 75 spring 48. A dog releasing device 48* is rotatably mounted on the frame 1, the lower end of the same having a nose 49 which may be engaged beneath the dog 46 to hold the latter disengaged from the pipe. The releasing device is provided with a crank arm 50 to which is connected one end of a retractile spring 51, the opposite end of the same being secured to the frame 1 whereby under the tension of the spring the device tends to move to a released position. In order that the device may be held against the tension of its spring I provide the device at its upper end with a lever 52 which is adapted to engage against the side of the pipe and held by the latter to prevent the rotation of said device, the pipe, thus serving to hold the device in a set position. Should the pipe fall, it is understood that as soon as its upper end passes the lever 52, the device 48* will 85 rotate and the nose of the device then disengage from the dog 46 to permit the latter to move under the tension of its spring to pipe locking position. In this manner the pipe while being lowered is effectively 90 guarded against its sudden fall as is now understood.

I claim:—

1. In an apparatus for raising and lowering pump pipes, a frame, alternately reciprocating clamps, a lever pivoted on the frame and operatively connected with said clamps, springs carried by the lever, hooks carried by the clamps and removably fitted to said springs, means connected with the 105 clamps adjacent the free ends thereof for operatively connecting the clamps together, and a yieldable member for causing the positive gripping of one of the clamps prior to the disengagement of the other of said 110 clamps.

2. In an apparatus for raising and lowering pump pipes, superposed reciprocating clamps, means for operatively connecting the clamps together, operating means for 115 said clamps, springs carried by said means and adapted for detachable engagement with said clamps, and a yieldable member disposed in contacting proximity to one of said clamps for causing the positive gripping of the latter with the pipe prior to the disengagement of the other of said 120 clamps.

3. In an apparatus for raising and lowering pump pipes, superposed reciprocating clamps, means for operatively connecting the clamps together, operating means for said clamps, springs carried by said means and adapted for detachable engagement with said clamps and an adjustable yieldable member for causing a positive gripping

of the latter with the pipe prior to the engagement of the other of said clamps. 10

In testimony whereof I affix my signature in presence of two witnesses.

CHARLES H. REUTER.
